UNITED STATES PATENT OFFICE

147,479

DESIGN FOR A PRINTED FABRIC

Ethelle Thompson, Los Angeles, Calif., assignor
to Ethelle, Inc., Los Angeles, Calif., a corpora-
tion of California

Application January 20, 1947, Serial No. 136,259

Term of patent 3½ years

(Cl. D92—1)

To all whom it may concern:

Be it known that I, Ethelle Thompson, a citizen
of the United States, residing at Los Angeles,
in the county of Los Angeles, State of California,
have invented a new, original, and ornamental
Design for a Printed Fabric, of which the following
is a specification, reference being had to
the accompanying drawing, forming part thereof.

The figure is a plan view of a piece of printed
fabric showing my new design, the broken lines
outlining a design unit between the selvage edges
at the top and bottom, which unit is repeated
in regular succession throughout the length of the
fabric, as indicated.

I claim:

The ornamental design for a printed fabric, as
shown and described.

ETHELLE THOMPSON.
